UNITED STATES PATENT OFFICE.

WILLIAM H. VOSS, OF DAVENPORT, IOWA.

WASHING-MACHINE.

1,285,486.

Specification of Letters Patent. Patented Nov. 19, 1918.

Application filed July 19, 1917. Serial No. 181,621.

To all whom it may concern:

Be it known that I, WILLIAM H. Voss, a citizen of the United States, residing at Davenport, in the county of Scott and State of Iowa, have invented certain new and useful Improvements in Washing-Machines, of which the following is a specification.

This invention relates to washing machines, and more particularly to such machines in which the lid may be swung back, or removed, without disconnecting the connecting rod from the driving journals.

With the old form of connecting rod, it is necessary before raising the lid of the tub to stop and go through the laborious operation of disconnecting or removing the connecting rod from the driving mechanism for the reason that in swinging back the lid (when the same is hinged) the distance between the points of connection of the driving mechanism with the two ends of the connecting rod increases, and unless the connecting rod were disconnected at one or both ends the full swing of the lid could not be obtained. In instances where the lid is not hinged, but removed bodily, this need for disconnecting the connecting rod would be even greater. This disconnection or removal of the connecting rod involves considerable time, labor, and vexation, all of which tends to decrease the efficiency and ease of operation of the machine. With the new form of connecting rod which I have invented, the foregoing and other possible difficulties are completely overcome, and the swinging back or complete removal of the lid made possible with no exertion or time necessary other than the mere operation of a simple latch.

Among the objects of this invention, therefore, is to provide such form of washing machine that by a single simple operation of the operator's hand, the connecting rod may be instantly converted into such condition that its length will be automatically increased as the lid is swung back or removed; further to effect the automatic locking of the parts of the connecting rod into a rigid unitary structure when the lid is returned to its operative position; further to form such rod of two telescoping parts that they may be completely separated should it be desired to entirely remove the lid, or merely extended without separation when the lid is swung back on its hinges;

further to provide a novel form of lock for such rod which will hold the rod in rigid non-extensible position when in operative position, and which by a simple touch of the operator's finger will permit the extension of the rod to take place when desired; further to provide such rod that will permit the removal or swinging back of the lid without disconnecting one or both ends of the rod from the journals which connect therewith; further to provide such combination of connecting rod with washing machine mechanism as to make possible a quick and easy separation as well as connection of the mechanism on the top of the tub with that below the tub; and further to provide such combination, construction and arrangements of parts as will result in a more simple, economical, and efficacious washing machine than heretofore known.

Further objects and advantages will appear as the following description proceeds, and while I have illustrated a preferred embodiment of my invention, I desire it understood that the same is susceptible of modification and change without departing from the spirit of my invention.

In the drawings:

Figure 1 is a side elevation of a washing machine embodying my invention, and showing the lid in closed position.

Fig. 2 is a view similar to Fig. 1, but showing the lid in open position and the connecting rod distended.

Fig. 3 is a detail in section of the upper portion of the connecting rod and showing the telescoping parts in closed and locked position.

Fig. 4 is a view similar to Fig. 3, but showing the parts in distended position.

Fig. 5 is a side elevation of the upper portion of Fig. 4.

Referring to the drawings:

Upon the tub 1 is a cover or lid 2, which is provided with suitable means for locking it in operative position thereon. Secured to the top of the lid 2 is suitable dasher operating mechanism, which comprises gearing located within the housing 3, and operatively connected with the dasher 4. This mechanism also comprises the crank arm 5, which is journaled in suitable bearings secured to the top of the lid 2. Upon the free end of the crank arm 5 is a journal 6, which is journaled in the upper end of the

connecting rod 7. Suitably journaled to the lower end of the connecting rod 7 is the journal 8 carried by the crank arm 9, which is mounted upon the drive shaft 10, which 5 drive shaft is driven by any suitable source of motive power, and which in the embodiment illustrated is mounted on the frame work beneath the tub.

The connecting rod 7 is composed of the 10 rod portion 11 and the tubular portion 12, which rod telescopes within the tubular portion 12 as shown. Upon the upper end of the rod 11 is a casting 13 carrying the latch 14 by means of the pivot 15, and which latch 15 is provided with the finger portion 16 and the catch 17. This latch 14 is pivoted as shown within the slot 18 provided in the casting 13, which casting is suitably fastened by threads, rivets, or otherwise, as 20 desired, to the end of the rod 11. On the lower end of the casting 13 is the shoulder 19, the function of which will later appear. The tubular portion 12 has mounted upon its upper end by means of screw threads or 25 other suitable connection, the transversely extending projection 20, the under face of which is beveled as at 21, this bevel being such that when the face 22 of the catch 17 is in engagement therewith, the relation between 30 these surfaces will be such as to hold the telescoping parts firmly locked against separation. When the parts 11 and 12 are completely telescoped, the shoulder 19 will be in engagement with the upper end of the 35 tubular portion 12, should this tubular portion extend through the projection 20, or in engagement with the upper end of the projection 20, should the tubular portion 12 not extend entirely therethrough; the particular 40 arrangement of the structure in this matter being a matter of choice. Upon the lower end of the tubular portion 12 is a suitable casting 23, which may be secured thereto by means of threads, and which will be locked 45 in position by means of the lock nut 24. The journal 8 of the crank 9 before mentioned is journaled within a suitable opening in this casing 23 and held therein by means of a cotter-key 25. The journal 6 of 50 the crank arm 5 is likewise mounted in an opening in the upper end of the casting 13, as shown in Figs. 1 and 2.

The operation of my improved washing machine is as follows: When the tub is in 55 use and the mechanism is in operative position, the connecting rod 7 will be in position shown in Fig. 1, with the rod portion 11 completely telescoped within the tubular portion 12 and the catch 17 of the latch 14 60 in engagement with the bevel surface 21 of the lateral projection 20. This engagement of the latch with the lateral projection securely holds the telescoping parts 11 and 12 of the connecting rod 7 rigidly together, so 65 that motion from the crank arm 9 may be

transmitted through the connecting rod 7 to the crank arm 5, and from thence through the dasher operating mechanism to the dasher within the tub, and the connecting rod will thus act as a unitary structure, the 70 same as though no telescoping parts had been provided. Should it be desired to open the tub and raise the lid thereof, this can be done without the labor and loss of time necessary in disconnecting one or both ends 75 of the connecting rod from the journals of the crank arms 5 and 9. This is accomplished by grasping the finger portion 16 of the latch 14, and raising the same slightly so as to disengage the catch 17 from the 80 bevel portion 21 of the projection 20. After these parts are disconnected, the lid 2 may be raised, and in so doing the rod portion 11 will be pulled out of the tubular portion 12 a distance necessary to accommodate the 85 movement of the crank arm 5, which is carried by the mechanism mounted on the top of the lid 2, which crank arm during the opening of the lid is given a movement in the arc of a circle, the center of which would 90 be on a line through the hinges of the lid. When the lid is open, the parts will be in the position shown in Fig. 2, where it will be noticed the rod portion 11 is withdrawn to a considerable distance from the tubular 95 portion 12, but still not entirely removed therefrom. After the catch 17 is disengaged from the lateral projection 20 the latch 14 may be dropped, and it will occupy the position shown in Figs. 2 and 4. When 100 it is desired, the lid may be closed and such closing movement will return the rod 11 within the tubular portion 12, and when the lid is completely closed, the position of the rod 11 and tubular portion 12 will be such 105 that they will be completely telescoped, and as the catch 17 passes over the projection 20, the weight of the latch 14 will by gravity cause the catch 17 to automatically engage the bevel portion under the projection 20, 110 thus securely locking the telescoping parts from further movement with relation to each other, after which the connecting rod will operate as a unitary structure to drive the dasher operating mechanism. 115

It will thus be seen that I have provided a mechanism in which the lid of the washing machine may be raised or opened without any further work, in so far as the connecting rod is concerned, than merely raising the 120 latch 14 from engagement with the projection 20, which as shown above, permits the rod portion 11 to be withdrawn the necessary distance from the tubular portion 12. Should it be desired to entirely remove 125 the lid 2, together with its attached mechanism, this can be done for the reason that the rod portion 11 continues of the same size to its lower end, thus permitting it to be entirely withdrawn from the tubular por- 130

tion 12 if desired. My improved structure results in considerable saving of time for the reason that in opening or removing the lid it is not necessary to disconnect either 5 end of the connecting rod from the crank arm journals as has heretofore been necessary in washing machines.

Having now described my invention, I claim:

- 10 1. In apparatus of the class described an extensible connecting rod comprising two telescoping parts, a journal bearing at the outer end of each of said parts, and a gravity latch automatically operable upon the telescoping of said parts to lock them together. 70
- 15 2. In apparatus of the class described an extensible connecting rod comprising two telescoping parts, one of said parts having a projection, and the other of said parts having 20 a gravity latch adapted to ride over said projection and lock therewith upon the telescoping of said parts. 80
- 25 3. In apparatus of the class described, an extensible connecting rod comprising a tubular portion having a journal bearing at one end, and a transverse projection at the other, a rod having a journal bearing at one end and a latch adjacent thereto, said rod being adapted to telescope into said tubular 30 portion whereby the length of said connecting rod may be increased, and said latch being adapted to engage with said projection, whereby the telescoping parts may be 90 rigidly locked in operative position. 95
- 35 4. In apparatus of the class described, an extensible connecting rod comprising a tubular portion having a journal bearing at one end, and a transverse projection at the other, a rod having a journal bearing at one 40 end and a latch pivoted adjacent thereto, said rod being adapted to telescope into said tubular portion whereby the length of said connecting rod may be increased, and said latch being adapted to engage with said 45 projection, whereby the telescoping parts may be rigidly locked in operative position. 100
- 50 5. In apparatus of the class described, an extensible connecting rod comprising a tubular portion having a journal bearing at one end and a transverse projection at the other, a rod having a journal bearing at one end and a pivoted latch adjacent thereto, said latch being provided with a finger operating 55 portion and a catch portion, said rod being adapted to telescope into said tubular portion and said catch portion to take under said projection whereby said telescoping parts may be rigidly connected in operative 110 position. 115
- 60 6. In apparatus of the class described, a connecting rod comprising a tubular portion having a journal bearing at one end and a transverse projection at the other, a rod having a straight portion and an end portion, 65 a journal bearing in said end portion and a latch pivoted adjacent thereto, a shoulder at the juncture of said end portion with said straight portion, a catch on said latch adapted to take under said projection when said shoulder abuts the end of the tubular 70 portion, whereby when said rod is completely telescoped into said tubular portion the latch will hold these parts rigidly locked together, and upon releasing said latch said telescoping parts may be extended. 75
7. In a washing machine in combination with a tub lid, a dasher operating mechanism on said lid and having a crank arm, a main drive shaft having a crank arm, and an extensible connecting rod operatively connecting said two crank arms whereby said lid and dasher operating mechanism may be swung back, or removed from the tub without disconnecting said connecting rod from 80 said crank arms. 85
8. In a washing machine in combination with a tub lid having dasher operating mechanism secured thereto, said mechanism comprising a crank arm, an extensible connecting rod to one end of which is journaled said crank arm, a main drive shaft having a crank arm which is journaled to the other end of said connecting rod, and locking means on said connecting rod whereby said rod may be rigidly locked in operative position or upon release of said locking means said rod may be extended in length for the purpose set forth and described. 90
9. In a washing machine in combination with a tub lid having dasher operating mechanism secured thereto, said mechanism comprising a crank arm, a telescoping connecting rod journaled to said crank arm and comprising a tubular portion and a rod portion telescoping into said tubular portion, a drive shaft having a crank arm journaled to the other end of said connecting rod, and locking means on said connecting rod whereby when said rod portion is completely telescoped into said tubular portion, these parts 100 may be rigidly locked in operative position. 105
10. In a washing machine in combination with a tub lid having dasher operating mechanism secured thereto, said mechanism comprising a crank arm, a telescoping connecting rod journaled to said crank arm and comprising a tubular portion and a rod portion telescoping into said tubular portion, a drive shaft having a crank arm journaled to the other end of said connecting rod, a latch on one of said telescoping parts and a projection on the other over which projection said latch engages whereby when said latch is released the telescoping parts may 110 be moved with relation to each other, and the connecting rod automatically extended as the tub lid is opened. 120
11. In a washing machine in combination with a tub, a lid hinged thereto, dasher operating mechanism on said lid, said mechanism com- 125

prising a crank arm, a telescoping connecting rod to one end of which is journaled said crank arm, a drive shaft having a crank arm journaled to the other end of said rod, and a gravity latch connecting the telescoping parts of said connecting rod together, whereby when said parts are completely telescoped said latch will automatically fall into position to rigidly lock said parts together, and when said latch is re-

leased said connecting rod may be extended to accommodate the opening of the tub lid.

In witness whereof, I hereunto subscribe my name to this specification in the presence of two witnesses.
